CLAIM

The ornamental design for a quick release valve cover
assembly, as shown and described.

DESCRIPTION

FIG. 1 is a front elevational view of a quick release
valve cover assembly showing our new design, the rear
being a mirror image of that shown;

FIG. 2 is a top plan view thereof;

FIG. 3 is a bottom plan view thereof;

FIG. 4 is a right side elevational view thereof, the left
side being a mirror image of that shown; and

FIG. 5 is a perspective view thereof.

FIG. 1

FIG. 2

FIG. 5
